CLAIM

The ornamental design for a self-adjusting offset pipe wrench, as shown and described.

DESCRIPTION

FIG. 1 is a perspective view of our self-adjusting offset pipe wrench showing our new design;

FIG. 2 is a right side elevation view thereof;

FIG. 3 is a left side elevation view thereof;

FIG. 4 is a top elevation view thereof;

FIG. 5 is a bottom elevation view thereof;

FIG. 6 is a front elevation view thereof; and,

FIG. 7 is a rear elevation view thereof.

The broken lines shown in FIG. 4 is included for the purpose of illustration and forms no part of the claimed design.
